[57] CLAIM

The ornamental design for a bow for a bottle, as shown
and described.

DESCRIPTION

FIG. 1 is a perspective view of a bow for a bottle showing
my new design wherein the broken line showing of
the bottle is for illustrative purposes only and forms no
part of the claimed design;

FIG. 2 is a front elevational view;

FIG. 3 is a rear elevational view;

FIG. 4 is a left side view;

FIG. 5 is a right side view;

FIG. 6 is a top plan view; and,

FIG. 7 is a bottom plan view.

FIG. 1.

FIG. 2

FIG. 3

FIG. 4

FIG. 5

FIG. 6

FIG. 7
